UNITED STATES PATENT OFFICE.

WILLIAM S. RISCO, OF MICHIGAMME, MICHIGAN.

NAME-PLATE HOLDER.

Application filed June 12, 1923. Serial No. 644,977.

To all whom it may concern:

Be it known that I, WILLIAM S. RISCO, a citizen of the United States, residing at Michigamme, in the county of Marquette 5 and State of Michigan, have invented certain new and useful Improvements in a Name-Plate Holder, of which the following is a specification.

The present invention relates to a name 10 plate holder and has for its principal object to provide a device of this nature consisting of an illuminated casing adapted to hold a transparent plate preferably having thereon the name of a city from which the 15 vehicle to which the device is attached is from.

An important object of the invention is to 20 provide a clip for locking the transparent plate in a closed position on the casing or holder.

Other objects of the invention are to provide a device of this nature having a simple 25 and efficient structure, one which is reliable, inexpensive to manufacture, durable, attractive in appearance, and well adapted to the purpose for which it is designed.

With the above and numerous other objects in view as will appear as the description progresses, the invention resides in certain 30 novel features of construction, and in the combination and arrangement of parts as will be hereinafter more fully described and claimed.

In the drawing—

Figure 1 is a perspective view of the device embodying my invention,

Figure 2 is a longitudinal section taken therethrough,

Figure 3 is a transverse section taken therethrough,

Figure 4 is a perspective view of the clip used for holding the transparent name plate on the holder, and

Figure 5 is a detail enlarged section taken 45 through one corner of the device.

Referring to the drawing in detail it will be seen that 1 designates the casing which is constructed with the back wall 2 including diverging side wings 3 terminating in the sides 4. The top and bottom walls 5 are substantially triangular in formation. A rectangular shaped flange 6 is arranged about the front edges of the side, top and bottom walls forming a frame which is 50 V-shaped in cross section as is indicated in Figure 3. One end of the frame, however,

is slotted as at 7 so that a transparent panel 55 preferably of celluloid and indicated at 8 may be passed through the slot and have its edges disposed in the channels formed by the frame 6. This transparent panel 60 is preferably formed of celluloid and has written thereon the name of the city or town 65 from which the automobile to which the device is attached is from. A source of illumination 9 is disposed within the casing 70 so that it may be lighted in the nighttime and the name of the town or city read from a considerable distance. This source of illumination 9 is preferably in the form of an 75 electric bulb which is attached to the rear wall 2 being threaded engaged with a nut 80 fixed to this wall on the interior thereof.

A clip 11 is attached to the end of the 85 transparent panel 4. As is disclosed to advantage in Figures 4 and 5 this clip includes a pair of spaced plates 12 one on each side of the panel. These plates are connected by a loop portion 13 which forms a gripping 90 member so that the panel may be slid in and out of engagement with the frame 6. On the end of one of the plates 12 there is provided a curved extension 14. This clip 95 is formed of resilient material and this curved extension will engage the extension 15 formed on one side wall 4 adjacent the slot of the frame and hold the panel 8 against accidental displacement. With a little force the curved portion 14 may be pulled from engagement with the extension 15 and will flatten out during the time the clip is being forced from or into the frame and because of the resilient nature of the clip this curved portion will resume its 100 normal configuration.

On the bottom edge of the frame a pair of slotted depending spaced plates 17 are 105 formed so that the usual license tag may be attached thereto. This device is preferably disposed in close proximity to the ordinary tail light on the automobile and the bulb 9 is controlled through the switch of this tail light.

Although I have described my invention with a certain degree of particularity it is to 110 be understood that numerous changes in the combination, arrangement and details of the parts may be resorted to without departing from the spirit of the invention or sacrificing any of its advantages.

Having thus described my invention what I claim as new is:—

1. A device of the class described including a casing having an opening, a frame disposed about the opening of the casing, a panel slidable in the frame, and a clip disposed on one end of the panel and including a resilient curved extension for engaging the frame and preventing accidental displacement of the panel.
2. In combination, a frame, a panel slid-
10 able in the frame, and a clip including a pair of spaced plates one on each side of the panel and a loop gripping portion connecting the plates, and a curved extension formed on the end of one of said plates,
15 said clip also being slidable through the

frame so that the curved extension may engage an inner end of the frame for holding the panel in position therein so as to prevent its accidental displacement.

3. As a new article of manufacture, a clip 20 designed for the purpose specified including a pair of flat spaced plates, a loop portion connecting the plates, and a curved resilient extension formed on the end of one plate.

In testimony whereof I affix my signature 25 in presence of two witnesses.

WILLIAM S. RISCO.
